UNITED STATES PATENT OFFICE

118,379

DESIGN FOR A STAPLING MACHINE

Arthur H. Maynard, Warwick, R. I., assignor to
Boston Wire Stitcher Company, Warwick, R. I.,
a corporation of Maine

Application October 31, 1939, Serial No. 87,951

Term of patent 14 years

To all whom it may concern:

Be it known that I, Arthur H. Maynard, a citizen of the United States, residing at Warwick, in the county of Kent and State of Rhode Island, have invented a new, original, and ornamental Design for a Stapling Machine, of which the following is a specification, reference being had to the accompanying drawing, forming a part thereof, in which:

Fig. 1 is a perspective view of a stapling machine showing my new design;

Fig. 2 is a plan view; and

Fig. 3 is a front view of the same.

I claim:

The ornamental design for a stapling machine, substantially as shown.

ARTHUR H. MAYNARD.
